UNITED STATES PATENT OFFICE.

AUGUST C. HUMMEL, OF CINCINNATI, OHIO.

FOLDING CRIB.

1,135,022.

Specification of Letters Patent. Patented Apr. 13, 1915.

Application filed May 4, 1914. Serial No. 836,060.

To all whom it may concern:

Be it known that I, AUGUST C. HUMMEL, a citizen of the United States, residing at Cincinnati, in the county of Hamilton and State 5 of Ohio, have invented certain new and useful Improvements in Folding Cribs, of which the following is a specification.

My invention relates to beds; and its object is to provide a child's bed or crib that 10 may be conveniently folded compactly with the bedding contained inside it, so as to be readily stored out of the way, as by placing it under a larger bed.

My invention consists in the parts and in 15 the details of construction and arrangement of parts as will hereinafter be more fully described and claimed.

In the drawings: Figure 1 is a general perspective view of a crib constructed according to my invention, the sides being dropped; Fig. 2 is a similar view of the same with the sides raised; Fig. 3 is a detail perspective view of one of the corners of the main frame; Fig. 4 is a general perspective 20 view of the crib completely folded; Fig. 5 is a horizontal cross section on the line $x-x$ of Fig. 3, better showing the construction of the corner of the main frame; Fig. 6 is a vertical section on a line corresponding to 25 the line $y-y$ of Fig. 5; Fig. 7 is a vertical section on a line corresponding to the line $z-z$ of Fig. 5; Fig. 8 is a vertical cross section through one of the corner posts of the head and the adjacent corner post of the 30 side, illustrating the clamping means therefor; Fig. 9 is a partial detail of the roller frame; Fig. 10 is a partial longitudinal section showing the preferred connection of the springs; and Fig. 11 is a similar view 40 showing a modification of the springs as applied to my improved crib.

The main frame 1 comprises the corner-blocks 2, longitudinal upper and lower rails 3 and 4, respectively at each side, and transverse upper and lower rails 5 and 6, respectively at the head and foot. The upper and lower rails 3 and 4 are preferably joined by a series of rungs 7 and the upper and lower rails 5 and 6 are joined by similar rungs 8. 45 Each corner-block 2 comprises a main outside part 9 of the full length of the block and to which the side rails 3 and 4 are joined, preferably by mortise and tenon as shown, and an inside back 10 of height only 50 that of the space between the upper and lower rails, this inside back 10 extending

over and being joined to the inner side 11 which is of the full height of the block, to which are joined the upper and lower rails 5 and 6, preferably by mortise and tenon as 60 shown. This formation of the corner-block 2 leaves the vertical channel 12 in front, and legs 13 lie in this channel 12 and are pivoted on transverse pins 14 passing through the outer and inner sides 9 and 11 of the 65 corner-block 2. Each pair of legs 13 at the head and foot, respectively, is rigidly joined by the roller frame 15, which has slots 16 next to the legs 13, receiving rollers or 70 wheels 17 to turn on shafts 18 extending 75 across the slots. If the legs 13, together with their rigidly joined roller frames 15, are swung down so that they stand vertical, with the main frame 1 horizontal, parts of these legs extending above the pivot pins 14 will lie in the vertical channels 12, and the rollers 17 will have their shafts 18 vertical; but the legs 13, with their rigidly attached roller frame 15, may be swung upward and inward on their pivots 14 so that 80 the legs 13 lie inside of and substantially flush with the lower side rails 4, and the rollers or wheels 17 will now have their shafts horizontal and will be adapted to bear on the floor and support the crib when in its 85 folded condition. The roller frame 16 has lateral extensions 19 past the legs 13, which extensions abut against the lower sides of the lower side rails 4 and limit the upward 90 swinging of the legs 13 and of the roller frame. The upward extensions of the legs 13 terminate about half way up the vertical slots 12, and have the outer sides of their end parts 20 cut away.

The crib has a head 21 and a foot 22 constructed similarly except that the foot is preferably slightly lower than the head. The head comprises corner posts 23 joined by upper and lower rails 24 and 25, respectively, with rungs 26 joining the upper and lower rails at intervals between the corner posts; and the foot 22 comprises corner posts 27 joined by transverse upper and lower rails 28 and 29, respectively, with rungs 30 joining the upper and lower rails 100 at intervals between the corner posts. The corner posts 23 and 27 are terminated upwardly at the transverse upper rail 21 or 28 as shown, or may be extended thereabove if desirable, for sake of appearance. However, each corner post 23 or 27 extends down 105 below its bottom transverse rail 25 or 29,

respectively, and occupies the upper part of the channel 12 in the corner-block 2 at the respective corner, these corner posts being pivoted on transverse pins 31 passing through the outer and inner sides 9 and 11 of the corner-block at the top, the pins 14 and 31 serving to reinforce the mortise and tenon construction of the rails and posts at the points where they are located; and 5
10 the inner side of the end part 32 of each post being cut away so that this end 32 of the corner post meets and fits together with the inversely presented upper end of the extension of the leg 13. The ends of the legs
15 13 and of these corner posts may be rounded to allow them to slide over each other freely, and prevent binding if they make contact while the crib is being unfolded. In folding the crib, the head and foot 21 and
20 22 are turned inward and downward until the corner posts 23 and 27 lie within and substantially flush with the upper side rails 3 of the main frame 1. When this head and foot are in their raised position, their lower
25 rails 25 and 29 will lie directly over the upper transverse rail 5 of the main frame 1 at the head and foot, respectively, these rails being brought as close together as practicable, and the inner upper edges 33 of
30 the rails 5 being preferably chamfered to permit the rails 25 and 29 to swing inward over them without engagement therewith. It is to accommodate the corner post and lower rail of the head or foot when swung
35 inward and downward that the corner-blocks have the inner back part 10 terminated short of the top and bottom of the block, as before described. The inner corners of these corner blocks may be chamfered as shown, to avoid harsh contact with
40 the occupant.

Each side 34 of the crib comprises corner posts 35 joined by longitudinal upper and lower rails 36 and 37, with rungs 38 joining the upper and lower rails at intervals 45 between the corner posts. Each of these sides is hinged to the respective side of the main frame 1 by means of double-acting hinges 39, fixed to the upper side of the upper rail 3 of the main frame and the lower side of the lower rail 37 of the side 34. With these double-acting hinges, the sides 50 may be turned inward and downward across the crib, over the inwardly and downwardly turned head and foot 21 and 22, respectively; or may be brought to vertical position as shown in Fig. 2, in which their corner posts 35 come adjacent the corner posts 28 and 27 of the head and foot, respectively; or may be turned outward and downward so 55 that the sides 34 lie down along the sides 34 of the main frame 1, as shown in Fig. 1. Such double-acting hinges may be obtained upon the market, and need not be described 60 in detail herein. I prefer to use the kind
65

illustrated, which have the advantage of allowing perfect freedom, in the movements above described, but which prevent the sides 34 from rising vertically from the main frame and which constrain both ends of the 70 sides 34 to remain down upon the main frame and prevent any irregular movement or twisting strains on the structure of the side 34.

From the foregoing description it will be 75 seen that the legs 13, with their roller frames 15 folded into the lower side of the main frame 1, and the head and foot 21 and 22, respectively, folded into the upper side, with the sides 34 folded down over these, 80 this folded condition being illustrated in Fig. 4, constitutes practically a box or crate with a hollow interior, which may readily hold the bed clothing, both when the crib is in unfolded condition for use and when 85 in folded condition for being placed out of the way. With the rollers or wheels 17 bearing on the floor, the entire folded crib may be readily rolled over the floor, and is thus readily rolled under a larger bed when 90 not in use.

As shown in Fig. 1, both of the sides 34 are dropped alongside the main frame, in which condition the crib resembles, a small 95 bedstead well adapted for use as a bed for older children; while with both sides raised and fastened to the head and foot as shown in Fig. 2, the device is adapted for fully performing its function as a crib, viz: to support a bed for a child and 100 prevent the child from leaving or from falling from this bed. Another very convenient adjustment of the device, with one of the sides dropped but with the other one raised and fastened to the head and foot, 105 permits the crib to be placed alongside a larger bed; and the crib, when it is set up, preferably being of such height that the bedding supported by the crib is substantially level with the bedding of the larger 110 bed. It is thus possible to have the crib and the larger bed practically continuous, as is frequently desirable in the management of young children. If desired the crib can be set up for use with the legs folded under, 115 thus forming a lower crib.

As before mentioned, the crib when folded is well adapted to be pushed under the larger bed; and it is very convenient, in setting up the crib, to first bring the leg members to their vertical positions, then folding the side 34 next to the larger bed outward and allowing it to be supported by the larger bed while the other side 34 is raised to vertical position, which then permits 120 either the head or foot to be raised, so that both of the sides 34 may be then secured to the raised head or foot by means of the clamps in the corner posts, after which the other end member, either head or foot, as the 125 130

case may have been, is raised and clamped to the sides. The clamps in the corner-blocks may then be fastened if desired, and, if both of the sides 34 are to be dropped at any time, it is necessary to fasten these clamps in the corner-blocks as before pointed out. In folding or collapsing the crib, the above described operations are performed in reverse order, it again being convenient to support one of the sides 34 on the larger bed while the other side is being unfastened and the head and foot folded inward. Then after the sides 34 are folded inward, the leg members are folded inward, bringing the crib down so that it may be again pushed under the larger bed.

The bedding may be supported in the main frame 1 in any approved manner. As herein shown, beams 40 at the head and foot of the crib, inside the corner-blocks 2, will suitably support the ends of the springs or other structure designed to support the bedding. As herein shown, each beam 40 consists of a length of angle iron with one of its legs fitting against the inner side of the corner-block, and its other leg lying upon the upper side of the lower rail 4 next to the corner-block, and being suitably fastened to the corner-block and rail 4, as by the screws illustrated. This angle iron beam, thus secured to these parts, reinforces the structure at these corners, and forms the support for the bedding. As shown in Fig. 10, a spring fabric 41 may have a bar 42 across its end, and this bar may have holes 43 while the beam 40 may have holes 44, and suitable links 45 passing through the holes in the bar and beam may hold the spring fabric 41 tightly stretched from end to end of the main frame of the crib. If a readily removable spring structure is desired, the spring fabric 41^a may have a complete frame 42^a within which it is stretched, and this frame 42^a may simply lie upon the beams 40 at the ends, as indicated in Fig. 11. Other well known means of supporting bedding in bedsteads may be adopted in connection with my improvement. In any case, the space within the main frame with the parts folded inward as described will be ample to accommodate the spring or other supporting structure as well as the mattress and such bedding as may be required in the crib, so that it is unnecessary to remove any of the bedding when the crib is to be put away. At the same time, the construction is open and fully ventilated, and with a minimum of crevices so that the bed may be conveniently kept clean and free from vermin.

With the lower end of the corner post 23 or 27 of the head or foot, respectively, lapsing over the upper end of the extension of the leg 13 as before described, it will be seen that if the head and foot are maintained in their upright positions they will maintain the

legs in their upright positions, with the roller frames 15 providing ample transverse bracing of these legs. It is also necessary to fasten the sides 34 to the head and foot when these sides are to be kept in their raised positions as shown in Fig. 2. Any suitable means may be provided for fastening these parts together in their raised positions; but I prefer to use the clamp 46, which is best shown in Fig. 8. This clamp comprises a plug 47, which is preferably cylindrical and tightly driven into a hole bored through one of the members; a sleeve 48, of similar formation, driven through a hole bored through the other member, the sleeve and plug being adapted to come substantially into alignment when the parts are brought together; and a screw 49 passing through the sleeve into the plug and having a head 50 outside the sleeve for turning the screw. The plug and sleeve preferably have their ends flush with the outer sides of the members, and have small radial lugs 51 and 52, respectively, which are indented into the material of the members, preventing the plug and sleeve from being pulled through the members, and preventing turning of the plug and sleeve. When the members are separated to be brought into their folded positions, the screw 49 will be screwed back in the sleeve 48 so that its end does not project, thereby avoiding striking of this end of the screw against the other member when the members are being brought into their raised positions, as would especially be liable to occur when the head and foot are being brought up while the sides 34 are raised. If the parts are held tightly together and the screw 49 screwed inwardly through the sleeve 48, its end will find and enter the threaded socket 53 which the plug has presented toward the sleeve 48, and the parts will then be held together by the screw 49. This screw will thus hold the parts together with its threads uniform throughout its length and with the interior of the sleeve 49 and the socket of the plug 53 having uniform threads; but the parts will not be rigidly clamped, owing to the fact that there will be such play as the threads of the screw allow; and also a failure to hold the parts very tightly together when starting the screw into the plug will result in their being slightly separated, and the screw will be unable to draw them together on account of the uniformity of the thread throughout. Such uniformly threaded arrangement will prove satisfactory in most cases, but not entirely so, for the above reason. Therefore, I prefer to provide the screw 49 with the end part 54 reduced, and to make the socket 53 of diameter to receive this reduced end part of the screw. By this proportioning of the parts, it is possible to provide the reduced end part, and the socket which it enters, of

higher pitch than those of the main part of the screw 49, as is indicated in Fig. 8, so that the advance of the reduced part 54 into the plug 47 will be faster than the advance 75 of the main part of the screw 49 through the sleeve 48, with the result that the part in which the plug 47 is fixed will be drawn toward and tightly clamped to the other part in which the sleeve 48 is fixed, due to the differential between the differently threaded 10 parts. It is to be understood that the difference in pitch of the different threads may be very slight, and thus provide a very powerful clamping effect, as is highly desirable to 15 give to the entire structure a high degree of stability when set up.

The head 50 is preferably made flat, and is adapted to come up very close to the sleeve 48 when the parts are clamped so as to be 20 out of the way. The tight clamping afforded by the preferred construction, and the very slight projection of the head 50, render the clamp difficult for a young child to operate, so that practically all liability 25 of loosening the clamps by the tampering of the child is eliminated; and the danger of the child collapsing any of the structure while in the bed therein is avoided, which, if it occurs, may result in serious injury to 30 the occupant of the bed, especially if it be a very young child.

Where the clamp fastens the sides 34 to the head and foot, the sleeve 48 is placed in the corner post 23 or 27 of the head or foot, 35 so that the head 50 of the screw is brought on the inside of the head or foot, out of the way, yet conveniently accessible. Where the clamps are applied to hold the head and foot up regardless of the sides 34, the sleeve 40 is placed in the back 10 of the corner-block 2, bringing the head of the screw on the inside of the main frame 1, where it is some distance below the top of the bedding therein, and entirely concealed and out of the 45 way, yet readily reached when required. By having the plug 47 and the sleeve 48 terminating flush with the outer surfaces of the parts which they are in, they will generally present a better appearance than if provided 50 with projecting heads, and this arrangement of the sleeve 48 permits the head of the screw to come up close, with the advantages above described.

The entire framework of course is most 55 readily constructed of wood and the pivot pins 14 of the legs and pivot pins 31 of the head and foot are also preferably of wood, such as dowel pins, which may be driven tightly and glued into the corner-block 2 60 but may fit the openings in the legs and corner posts loosely. The plugs, sleeves and screws of the clamps of course should be made of metal. However, it will be understood that the details of my invention 65 may be varied to adapt it for construction

with other materials, such as the construction of all or part of the framework of metal.

From the foregoing it will be understood that my invention is capable of some modification, and therefore I do not wish to be understood as being limited to the precise examples herein shown, but only as defined in the following claims.

I claim—

1. In a device of the character described, a main frame comprising a corner-block, an upper inwardly folding member and a lower inwardly folding member, said corner-block having a vertical channel, and said upper and lower member lying in the channel, the ends of said members meeting, and the end of one engaging over the end of the other, means pivoting each of the members in the channel, whereby their ends may swing outward from the channel, said corner-block being cut away at its lower and upper ends inward from the channel to permit said members to fold inward thereacross when their end parts swing outward, and means 80 for securing the member with its end engaging over the other member.

2. In a device of the character described, a main frame comprising a corner-block, an upper inwardly folding member and a lower 95 inwardly folding member, said corner-block having a vertical channel, and said upper and lower member lying in the channel, the ends of said members meeting, and the end of one engaging over the end of the other, means pivoting each of the members in the channel, whereby their ends may swing outward from the channel, said corner-block being cut away at its lower and upper ends inward from the channel to permit said members to fold inward thereacross when their end parts swing outward, and means 100 for securing the member with its end engaging over the other member, said main frame also comprising transverse and longitudinal rails, and the pivoting means of said members engaging with said rails to hold the rails to the corner block.

3. In a device of the character described, a main frame comprising a corner-block, an 115 upper inwardly folding member and a lower inwardly folding member, said corner-block having a vertical channel, and said upper and lower members lying in the channel, the ends of said members meeting, and the end 120 of one engaging over the end of the other, means pivoting each of the members in the channel, whereby their ends may swing outward from the channel, said corner-block being cut away at its lower and upper ends 125 inward from the channel to permit said members to fold inward thereacross when their end parts swing outward, and means for securing the member with its end engaging over the other member, said main 130

frame comprising longitudinal rails joined to the corner-blocks above and below, and transverse beams extending across said main frame and secured to the corner-blocks and 5 to the upper sides of the lower longitudinal rails, forming supporting means for bedding in the device and adapted to reinforce the connection of said rails to said corner-blocks.

10 4. In a device of the character described, a main frame, an upper inwardly folding member and a lower inwardly folding member, the ends of said members meeting and the end of one engaging over the end of the 15 other, means pivoting each of the members to the main frame, and means for securing said member with its end engaging over the other member, this latter member being disengageable from the end which engages over 20 it, and being adapted to be folded inwardly

while leaving the other member to be secured in outwardly folded position.

5. In a device of the character described, a main frame, an upper inwardly folding member and a lower inwardly folding member, the ends of said members meeting and the end of the upper member engaging over the end of the lower member when the members are folded outwardly, means pivoting each of the members to the main frame, and 25 means for securing the upper member in outwardly folded position, said lower member being disengageable from the upper member, and adapted to be folded inwardly while leaving the upper member to be secured in outwardly folded position. 30 35

AUGUST C. HUMMEL.
